TONE DEFLECTOR FOR GRAND PIANOS

Herschel E. Tower, Cincinnati, Ohio, assignor to
The Baldwin Company, Cincinnati, Ohio

Application October 3, 1936, Serial No. 103,885

5 Claims. (CL. 84—189)

When a grand piano is placed in a room over a carpet, the tone waves from the under side of the soundboard are directed against the carpet, resulting in a damping effect, owing to the absorption of sound by the carpet material. The present invention overcomes such a defect by deflecting the tone waves from the under side of the board to each side of the piano, by employment of a number of vanes of sounding board material. The use of a number of vanes assists additionally in such deflection by the reflections taking place from any one vane to the adjoining vanes.

In the drawing:

15 Fig. 1 is a view of a grand piano from above, with the plate and soundboard removed, so as to show the construction and placement of my vanes in an exemplary embodiment.

20 Fig. 2 is a cross-section of a grand piano taken lengthwise, and showing the relationship of my vanes to the soundboard and strings.

Fig. 3 is an end view of two vane structures in relative positions and as if viewed from the front of the grand piano.

25 Fig. 4 is a detail of a deflector vane.

A piano case 1 has a front rail structure 2. A soundboard 3 is glued to the structure 2 and the inner rim 4 of the case 1. A plate 6 is fastened to the inner rim of the case 1, as at 7. A number of strings 8 are stretched on the plate 6 and actuated by hammers 9, as is usual in piano construction. These strings pass over a bridge or bridges 18; and the vibrations of the strings when struck by the hammers 9 are thus imparted to the soundboard 3, also as is usual in piano construction.

40 A supporting post 10 is attached to the case 1 and extends from the front rail structure 2 to a point in the rear part of the case 1, where it is attached to the inner rim 4 as indicated at 5, in Figure 1. Supported in the piano case 1, adjacent to the under side of the soundboard 3 and in the spaces between the post 10 and the sides of the case 1, are two sets of vane structures 11 and 12. Each of the structures 11 and 12 contains a number of vanes 13 of sounding board material, attached as shown, to end pieces 14 and 16 and 15 and 17. The vanes 13 extend lengthwise in a direction parallel to the lengthwise direction of the post 10 and, in the direction of their widths extend downwardly and outwardly toward the sides of the case 1.

45 As can be readily understood, by the use of the vane structures described, tone waves from the under side of the soundboard are diverted

from a downward direction to a direction having a horizontal component. Such diversion has an advantage whether or not carpeting material be on the floor under the piano, since, as the result, the waves strike the floor at such angles as to be 5 reflected outwardly.

Many modifications can be made in my invention. I have shown in the above that the tone waves are deflected to both sides of the piano. As one modification, the vanes can be placed at 10 such angles as to deflect the waves to one side only, say the curved or right hand side. Other modifications can be made to fit various post structures.

What I claim as my invention is:

15 1. In a grand piano a case having a rim, a rail extending across said rim at the forward end thereof, a soundboard resting on said rim and said rail, and tone deflectors in said case below said soundboard, said deflectors being flat panel-like structures of sound reflecting material and of elongated shape, said deflectors being located substantially horizontally as respects their length but being tilted at an angle to the horizontal widthwise and fixed in such a position as to deflect outwardly sound waves emanating downwardly from said soundboard.

20 2. In a grand piano a case having a rim, a rail extending across said rim at the forward end thereof, a soundboard resting on said rim and said rail, and tone deflectors in said case below said soundboard, said deflectors being flat panel-like structures of sound reflecting material and of elongated shape, said deflectors being located substantially horizontally as respects their length but being tilted at an angle to the horizontal widthwise and fixed in such a position as to deflect outwardly sound waves emanating downwardly from said soundboard, said tone deflectors extending in the direction of the length of said piano whereby said sound waves are deflected outwardly sidewise as respects the length of said piano.

25 3. In a grand piano having a case, a rim with in said case, a rail extending across said rim at the forward end thereof and a brace extending between the rear portion of said rim and said rail, a soundboard resting on said rim and said rail, said brace being located below said soundboard, and a plurality of tone deflecting means 30 extending in the general length of said piano and lying in the same general plane as said brace and on either side thereof, said tone deflecting means comprising panel-like structures of sound reflecting material interspaced from each other 35 40 45 50 55

and supported at their respective ends, said tone deflecting means being substantially horizontal in the direction of their length but tilted widthwise at an angle to the horizontal and fixed at an angle to deflect outwardly sound waves emanating downwardly from said soundboard.

4. A structure as claimed in claim 3 wherein the tone deflecting means on opposite sides of said brace have an opposite angularity widthwise, whereby to reflect sound waves outwardly with respect to both sides of said piano.

5. In combination with a grand piano having a case, a rim within said case, a rail extending across the front portion of said rim and a sound-board resting on said rim and rail, at least one

sound reflecting structure located below said soundboard, said structure comprising end members adapted to be fastened to said rim and rail and sound deflecting members attached to and extending between said end members, said sound deflecting members being elongated panel-like structures of sound reflecting material inter-spaced from each other, extending substantially horizontally with respect to their length but tilted widthwise and fixed at such an angle to the horizontal as to deflect outwardly sound waves emanating downwardly from said soundboard when said structure is in place in said piano beneath said soundboard.
